UNITED STATES PATENT OFFICE.

JOHN W. JONES AND WALTER S. REYNOLDS, OF SYRACUSE, NEW YORK.

DRAFT-PIPE AND DAMPER CONSTRUCTION FOR HEATERS.

Application filed June 7, 1921. Serial No. 475,665.

To all whom it may concern:

Be it known that we, JOHN W. JONES and WALTER S. REYNOLDS, citizens of the United States, and residents of Syracuse, in the county of Onondaga and State of New York, have invented a certain new and useful Draft-Pipe and Damper Construction for Heaters, of which the following is a specification.

10 This invention relates to heaters and has for its object a particularly simple, efficient and compact arrangement of the draft pipe and dampers, and means for controlling the opening and closing of one damper from 15 the other. The invention consists in the novel features and in the combinations and constructions hereinafter set forth and claimed.

In describing this invention, reference is 20 had to the accompanying drawing in which like characters designate corresponding parts in all the views.

Figure 1 is an elevation, partly in section of a heater embodying our invention. 25 Figure 2 is an enlarged sectional view through the draft pipe illustrating the operation of the dampers.

1 designates the heater having a draft pipe 2, the heater here shown being of the 30 type for heating the water of a hot water circulating system and having a thermostatic or other device 3 operated by the temperature or pressure of the water in any well known manner.

35 The construction of this device forms no part of our invention, and as the construction thereof is well known to those skilled in the art, further description is thought to be unnecessary.

40 This invention comprises a draft pipe for heaters, such pipe having a smoke chamber extending horizontally transversely thereof and formed with an air inlet in one of its lateral sides, the lower part of the pipe proper opening through the bottom of the 45 chamber and the outlet being through the top of the chamber, such chamber being of greater transverse dimension than the draft pipe whereby the chamber is an enlargement of the draft pipe, a damper for controlling the passage for the pipe into the 50 chamber through the bottom thereof, a damper for controlling the air inlet, and means for controlling the dampers.

55 The damper mechanism comprises two

dampers and motion transmitting and reversing means between the dampers whereby the opening of one damper causes the other damper to close and the closing of the first damper causes the other damper to open, and means for controlling the opening and closing of the first damper.

In the illustrated form of this invention, the dampers are gravity operated, that is, they are moved to their closed position by gravity.

20 is the horizontally and transversely extending chamber or enlargement of the draft pipe.

4 and 5 designate the dampers, the damper 4 being located in the upright portion of the draft pipe and movable vertically toward and from the seat 6 therein, and the damper 5 being arranged to control the cold air inlet 7 of the draft pipe, this inlet extending laterally from the upright portion of the draft pipe and above the seat 6. The motion transmitting and reversing means between the dampers 5, 6 includes a lever 8 pivoted at 9 between its ends to the draft pipe and connected at one end by a suitable link 10 to the damper 4 and having its other arm 11 extending into and lengthwise of the air inlet and arranged in the path of the damper 5 in order to be engaged and operated thereby when the damper 5 approaches its closed position. The damper 5 is here shown as a flap pivoted at its upper edge at 12. As the damper 5 reaches its closed position it depresses the arm 11 of the lever, thus raising the other end of the lever to lift or open the damper 4, and when the damper 5 is opened the damper 4 closes by gravity.

The damper 5 is operated by the thermostatic means 3 which as here illustrated has an arm 13 connected by a link 14 to the damper 5, the arm being provided with a suitable weight 15 which acts to close the damper 5.

Owing to the chamber 20 being an enlargement of the smoke pipe, the construction of the heater itself is simplified and also the damper control can be applied to any heater by supplying the heater with the smoke pipe having the transverse enlargement or smoke chamber and the dampers associated with such chamber.

In operation, as the temperature rises or the water expands, the thermostat or simi-

lar device 3 lifts the arm 13 causing the arm to open the cold air damper 5 and close the damper 4 and as the temperature drops, the arm 13 drops and the weight 5 thereof closes the cold air damper 5 and opens the damper 4.

What we claim is:

1. In a heater, a draft pipe having a chamber extending horizontally transversely thereof, the chamber having an air inlet in one of its lateral sides and the pipe proper opening through the bottom of the chamber, a damper for controlling the passage from the pipe into the chamber through the bottom thereof, a damper for controlling the air inlet and means for operating the dampers, substantially as and for the purpose described.
2. In a heater, a draft pipe having a chamber extending horizontally transversely thereof, the chamber being of greater dimension than the draft pipe, whereby the chamber is an enlargement of the draft pipe, the chamber being formed with an air inlet in one of its lateral sides, a damper

for controlling the passage from the pipe into the chamber through the bottom thereof, a damper for controlling the air inlet and means for controlling the dampers, substantially as and for the purpose specified. 30

3. In a heater, a draft pipe having an upwardly extending portion provided with a chamber extending horizontally transversely of the upwardly extending portion of the pipe, the chamber being of greater dimension than the draft pipe, whereby the chamber is an enlargement of the draft pipe, the chamber being formed with an air inlet in one of its lateral sides, a damper for controlling the passage from the pipe into the chamber through the bottom thereof, a damper for controlling the air inlet and means for operating the dampers, substantially as and for the purpose set forth. 35

In testimony whereof, we have hereunto signed our names at Syracuse, in the county of Onondaga and State of New York, this 9th day of April, 1921.

JOHN W. JONES.

WALTER S. REYNOLDS.
